(No Model.)

J. MATTHEWS & J. GILMER.
HOUSE DOOR LETTER BOX.

No. 447,254.

Patented Feb. 24, 1891.

UNITED STATES PATENT OFFICE.

JOSE MATTHEWS AND JOSEPH GILMER, OF SAVANNAH, GEORGIA; SAID
MATTHEWS ASSIGNOR TO SAID GILMER.

HOUSE-DOOR LETTER-BOX.

SPECIFICATION forming part of Letters Patent No. 447,254, dated February 24, 1891.

Application filed October 28, 1890. Serial No. 369,550. (No model.)

To all whom it may concern:

Be it known that we, JOSE MATTHEWS and JOSEPH GILMER, citizens of the United States, residing at Savannah, in the county of Chat- 5 ham and State of Georgia, have invented cer- tain new and useful Improvements in Mail- Boxes for Offices, Private Houses, or Public Buildlings; and we do hereby declare the following to be a full, clear, and exact description 10 of the invention, such as will enable others skilled in the art to which it appertains to make and use the same.

The special object of the invention is to make a mail-box for private houses, in which 15 the carrier may simultaneously deposit the mail, strike a bell or gong, and lock a cover over the entrance-slot, thus preventing a possibility of any of the letters being removed by the insertion of any device through said slot.

20 Figure 1 of the drawings is an elevation of my invention attached to a door, and Fig. 2 a vertical section thereof.

In the drawings, A represents a door hav- 25 ing the vertical slot *a*, through which the car- rier is expected to drop his mail into the box B. Over the inside of box and of door is a slot-cover C, which has a knob *c'*, connected by an elastic or other spring D to another knob *a'* on the inside of door. This spring D 30 holds the cover C above the slot *a* until the mail has been deposited by the carrier, who draws down the cover C until the spring-latch E shoots out behind it at the point *e*, thus pre-

venting it from uncovering the slot until the latch has been withdrawn by some one in the 35 house. *c* is a finger-piece, by which the cover C may be conveniently pulled down by the carrier. The cover C has two studs, (marked 1 and 2,) which, as it is pulled down, strike successively on end of the elbow-lever H, 40 which pulls the wire *h*, connecting with an ordinary striking-bell G, thus making two strikes quickly following one another, so as to distinguish from the single strike of the ordinary house-bell. This device thus not only 45 saves much time to the letter-carrier, but an- nounces when the mail is deposited, and closes all access thereto from the outside. The owner may, of course, keep the box under lock and key, so that no one in the house can take 50 out the mail.

What we claim as new, and desire to protect by Letters Patent, is—

The combination, with a vertically-slotted house-door, of an inside box B, secured thereto, 55 a slotted cover C, retracting-spring D, spring-latch E, and lever H, connecting with a strik- ing-bell, said cover provided with the studs 1 2, as and for the purpose set forth.

In testimony whereof we affix our signatures 60 in presence of two witnesses.

JOSE MATTHEWS.
JOSEPH GILMER.
